UNITED STATES PATENT OFFICE.

JOHN A. SPENCER, OF LONG BEACH, CALIFORNIA.

AEROPLANE.

1,303,737.

Specification of Letters Patent.

Patented May 13, 1919.

Application filed May 20, 1918. Serial No. 235,733.

To all whom it may concern:

Be it known that I, JOHN A. SPENCER, a citizen of the United States, residing at Long Beach, in the county of Los Angeles and 5 State of California, have invented new and useful Improvements in Aeroplanes, of which the following is a specification.

My invention relates to aeroplanes, and consists of the novel features herein shown, 10 described and claimed.

Figure 1 is a perspective of an aeroplane embodying the principles of my invention.

Fig. 2 is a perspective showing a modified form.

15 Fig. 3 is a detail of the mounting of one of the motor driven propellers used in Fig. 1.

Fig. 4 is a detail of the mounting of one of the motor driven propellers used in Fig. 2.

20 Fig. 5 is a diagram of the system for mechanically controlling the propellers shown in Fig. 1.

Fig. 6 is a diagram of the electric system used in Fig. 1.

25 The floats 1 and 2 are straight and parallel longitudinally and V-shaped in cross-section, and the tops of the floats 1 and 2 are built integral with the deck 3, there being an arch-shaped passage 4 between the floats 30 1 and 2 and below the deck 3 and extending from end to end. The planes 5 and 6 are mounted above the deck 3 and supported upon posts 7 and 8. Compartments 9 and 10 are formed from the upper face of the

35 deck 3 at the transverse center and near each end. Supporting arms 11 and 12 extend horizontally outwardly from one side of the deck 3, and similar supporting arms 13 and 14 extend horizontally outwardly 40 from the other side of the deck, the arms 11 and 13 being in transverse alinement, and the arms 12 and 14 being in transverse alinement. A shaft 15 is mounted to extend through bearings 16 in the outer ends of the

45 arms 11 and 13, said shaft extending entirely through the deck 3. A similar shaft 17 is mounted in similar bearings in the outer ends of the supporting arms 12 and 14 and extends through the deck 3. A motor 50 shaft bearing 18 is fixed upon one end of the shaft 15 crosswise of the shaft so that the bearing 18 will rotate endwise when the shaft 15 rotates. The motor casing 19 is fixed to one end of the bearing 18. The motor 20 is mounted in the motor casing 19. The motor shaft 21 extends through the

bearing 18 from the motor 20 and the propeller 22 is fixed upon the opposite end of the shaft 21 from the motor 20. In a like manner the propeller 23 is mounted upon the other end of the shaft 15 and the propellers 24 and 25 are mounted upon the ends of the shaft 17. The propeller 23 is driven by a motor 26 and the propellers 24 and 25 are driven by motors 27 and 28. A shaft 29 is mounted longitudinally of the deck 3 and one end of the shaft 29 is connected to the shaft 15 by bevel gears 30 and 31 and the other end of the shaft 29 is connected to the shaft 17 by bevel gears 32 and 33. A crank 34 is mounted in a position convenient to the operator, a wheel 35 is fixed upon the crank 34, and a chain or belt 36 runs over the wheel 35 and over a wheel 37 fixed upon the shaft 29 so that by operating the handle 38 70 of the crank the shaft 29 is rotated one way or the other to rotate the shafts 15 and 17, and the rotation of the shafts 15 and 17 swings the propellers 22, 23, 24 and 25 in planes concentric to the axes of the shafts 80 15 and 17, as required to change the direction of pull or push of the propellers.

The internal combustion engine 39 operates the dynamo 40. The storage battery 41 is connected to the dynamo 40 through an 85 automatic circuit breaker 42 and through the line 43. The main line from the dynamo 40 runs through the line 45, the switch 46, and the line 47, to the switches 48, 49, 50, 51 and 52. The switch 48 controls the motor 27, the switch 49 controls the motor 26, the switch 50 controls the motor 20, the switch 51 controls the motor 28, and the switch 52 controls the motor 53 over the line 54, said motor 53 being connected to 90 operate the crank shaft 55 of the engine 39, so that when the storage battery 41 is charged, closing the switches 46 and 52 will place the motor 53 in the storage battery circuit and start the motor 53 to start the 100 engine 39.

The lines 56, 57, 58 and 59 run from the switches 48, 49, 50 and 51, respectively, to the motors 27, 26, 20 and 28, respectively. The line 58 is attached to a binding post 60 105 upon the bearing 16 upon the arm 11, an insulated conducting plate 61 is located between the face 62 of the bearing 16 and the face 63 of the bearing 18, a binding post 64 is connected to the plate, and a wire 65 connects the binding post 64 to the motor 20 110 so as to make a rubbing contact by which

the current may pass from the line 58 to the motor 20 while the motor 20 and propeller 22 are swinging around the axis of the shaft 15. In a like manner electric connections 5 are made from the wires 56, 57 and 59 to the motors 27, 26 and 28.

As before suggested, the propellers 22, 23, 24 and 25 swing around the axes of the shafts 15 and 17 so that by manipulating the 10 handle 38 of the crank 34 the operator may control the direction of pull or push of the propellers as required to go straight up, go ahead, or go backward.

The floats 1 and 2 will support the aeroplane upon the surface of water like a catamaran and when it is desired to raise straight up from the water or from the ground the handle 38 of the crank 34 is operated to swing the propellers to rotate on vertical 15 axes so the force of propulsion will be in vertical lines, and then the force of propulsion will be exerted to raise the aeroplane straight up from the land or water like a helicopter, and when the aeroplane has 20 reached the desired height, reducing the speed of the motors, to a proper point will maintain the aeroplane practically in a stationary position. When desired, the crank 25 34 may be operated to swing the propellers 30 to inclined or horizontal positions, as required to move the aeroplane forwardly or backwardly. In this way the aeroplane is under the control of the operator and the motors may be run continuously to lift the 35 aeroplane or to move it forwardly or backwardly or at any desired angle, and when the aeroplane is going in one direction and it is desired to slow up or stop, the crank 34 may be operated to turn the propellers end 40 for end, thus reversing the direction of propulsion without stopping the engine or stopping anything.

In the modified construction shown in Figs. 2 and 4 the propeller constructions 45 66 and 67 are mounted in the passage 4 and the power mechanism 68 operates these propeller constructions.

The details of the propeller construction 50 66 are as follows: The beam 69 is mounted horizontally, transversely of the passage 4, and in the upper part of the passage, and the beam is supported by bearings 70 and 71 fixed to the inner faces 72 and 73 of the floats 1 and 2. The motor frame 74 is fixed 55 to the beam 69, the motor 75 is mounted in the frame 74, and the motor shaft 76 extends from the motor 75 through a bearing 77 transversely of the beam 69 and at its center, and the propeller 78 is fixed upon the 60 end of the motor shaft 76. In a like manner the propeller construction 67 is mounted at the other end of the passage 4. A stub-shaft 79 is fixed to the beam 69 and extends through the bearing 71. A bevel 65 gear 80 is fixed upon the stub-shaft 79. A

shaft 81 is mounted longitudinally of the float 2 and a bevel gear 82 fixed upon the shaft 81 meshes with the gear 80. In a like manner the other end of the shaft 81 is connected to the propeller construction 67. A 70 wheel 83 is fixed upon the shaft 81, a crank shaft 84 is mounted in position convenient to the operator, a wheel 85 is fixed upon the crank shaft 84, a belt or chain 86 runs over the wheel 85 and the wheel 83, and the crank 75 shaft 84 is operated by a hand-crank 87, so that the swing of the propellers may be controlled by manipulating the handle 87. The electric and generating system shown in Fig. 80 6 and described with reference to Fig. 1 may be used in the power plant 68, the only difference being that there are two motors and propellers to operate instead of four.

If desired, the propeller constructions shown in Figs. 2 and 4 may be added to the 85 construction shown in Fig. 1.

Wheels 88 may be mounted upon the bottoms of the floats 1 and 2 to roll upon the ground.

It is to be understood that the propellers 90 may be of any suitable design, that the blades may be set to pull or push, and that the propellers may be on the front ends of the shafts or on the rear ends of the shafts.

The drawings are to be considered as conventional and diagrammatic and it is to be understood that the form of aeroplane is not essential and that rudders or steering apparatus, safety appliances, and so on, may be applied as desired. 95

The leading feature of my invention is the mounting of a propeller to swing around an axis transverse of the rotating axis, and to provide means for driving and swinging the 100 propeller.

Any desired number of propellers may be used and any suitable system of wiring and generating power may be used.

Various other changes may be made in the details of construction without departing 110 from the spirit of my invention as claimed.

I claim:

1. In an aeroplane, two straight parallel V-shaped floats, a deck built integral with the tops of the floats and connecting the floats together and forming an arch-shaped passage between the floats below the deck, posts extending upwardly from the deck, and lifting planes mounted upon the posts. 115

2. In an aeroplane, two straight parallel floats; a deck connecting the tops of the floats, there being compartments formed from the upper face of the deck at the transverse center and near each end; supporting arms extending horizontally outwardly from 120 the sides of the deck in transverse lines; a shaft mounted in the forward pair of supporting arms; a second shaft mounted in the rear pair of supporting arms; motors mounted upon the ends of the shafts, the axes of the 125 130

motors being crosswise of the axes of the shafts; propellers upon the motors; a third shaft mounted longitudinally of the deck and geared to the first two shafts; a crank conveniently mounted in one of the compartments; a wheel fixed upon the crank; a wheel fixed upon the third shaft; and a connection between the two wheels so that by manipulating the crank the direction of pull of the propellers may be regulated.

3. In an aeroplane, two straight parallel floats; a deck connected to the tops of the floats, there being a compartment formed from the upper face of the deck at the trans-

verse center; supporting arms extending

horizontally and transversely of the floats; shafts mounted in the supporting arms; motors mounted upon the shafts, the axes of the motors being crosswise of the axes of the shafts; propellers upon the motors; a third shaft mounted longitudinally and geared to the transverse shafts; a crank conveniently mounted in the compartment; a wheel fixed upon the crank; and a connection between the crank wheel and the third shaft, so that by manipulating the crank the direction of pull of the propellers may be regulated.

In testimony whereof I have signed my name to this specification.

JOHN A. SPENCER.
